Mary Jane Johnston

UNITED STATES PATENT OFFICE.

MARY JANE JOHNSTON, OF MILWAUKEE, WISCONSIN.

PORTABLE FIRE-ESCAPE.

SPECIFICATION forming part of Letters Patent No. 706,666, dated August 12, 1902.

Application filed February 3, 1902. Serial No. 92,385. (No model.)

To all whom it may concern:

Be it known that I, MARY JANE JOHNSTON, a citizen of the United States, and a resident of Milwaukee, in the county of Milwaukee and 5 State of Wisconsin, have invented certain new and useful Improvements in Portable Fire-Escapes; and I do hereby declare that the following is a full, clear, and exact description thereof.

10 My invention has for its object to provide a fire-escape which is simple in construction, light, and of such proportions as to be conveniently placed in the satchel of a traveler; and it consists in certain peculiarities of construction and combination of parts to be fully 15 set forth hereinafter with reference to the accompanying drawings and subsequently claimed.

In the said drawings, Figure 1 is a general 20 perspective view illustrating the manner of attaching my device when in operation. Fig. 2 is a detail elevation of my device with parts in section and parts broken away to better illustrate my invention; and Fig. 3 is a cross- 25 section of the same on line 2 2 of Fig. 2, showing the locking-pawl and ratchet-wheel in detail.

Referring by letters to the drawings, A is the spindle, and B B' a pair of spools secured 30 thereto in any desired manner, and between the latter, loosely mounted upon the spindle, is a hollow handle C, which is provided with a series of longitudinal openings or slots a and is bored out at either end to form a bearing 35 in which the spindle A revolves. A ratchet-wheel E is secured to the spindle between the handle and the spool B and is opposed by a pawl D, which is pivoted between ears b, projecting from the adjacent end of 40 the handle C, and is held against the teeth of the aforesaid ratchet-wheel by a spring c, interposed between the handle and the tail of the pawl, the latter projecting toward the center of the handle in such a position so as 45 to be readily controlled by the operator.

The spool B has projecting from its inner disk a friction-band B², which when engaged by the back of the pawl D serves as a brake. A stirrup I' is suspended from the spindle A 50 by means of metal cables I, secured to thimbles H, loosely mounted upon said spindle at either end thereof, and outside of the spools

B B' and upon the tread of said stirrup I' is preferably secured an elastic band e, into which the foot is slipped and securely held 55 when the person operating the fire-escape is descending.

A lowering-cable F, having its ends secured to the spools and normally wound upon the latter, is provided for lowering the device, and 60 an elevating-cable G is wound around and secured to the spindle A within the hollow handle and in the opposite direction from the first-named cable, the free end of which may be readily drawn out through one of the slots 65 a of the aforesaid handle when it is desired to elevate the device.

As illustrated in Fig. 3 of the drawings, when it is desired to put the device in operation the cable F is thrown over any available fixture 70 K in the apartment, and the device is then drawn out through the window, the cable F having a spacing-rod J to keep the former approximately in line with the spools. The person grasps the handle with one hand and 75 after placing the foot in the stirrup presses the tail of the pawl with the thumb. This frees the handle from the spindle, and the device will descend by gravity, the spindle and the several parts secured thereto revolving, 80 thereby causing the lowering-cable to unwind, the speed being governed by the operator pressing the back of the pawl against the friction-band B² or stopped entirely by releasing the pawl D, which would then be forced into 85 the teeth of the ratchet by its spring and lock the handle and spindle together.

Should it be desired to return the device after the first person has been lowered, the free end of cable G would be drawn out through 90 one of the slots a of the handle, and as it was pulled it would revolve the spindle and wind up the lowering-cable while the raising-cable G was unwinding until the device was raised to the position from where it had been started, 95 it being understood that when in this latter position the diameter of the coil of cable G, which has not been unwound entirely from spindle A, is still greater than the diameter of the coil of cable F, wound upon the spools 100 B B', and if it was not desired to use the device after the lowering-cable was wound it would be necessary to wind up the raising-cable. For this purpose I have provided a

crank *d*, pinned to one end of the spindle, which when revolved will wind up the last-named cable, so that the device can be stored away.

5 Having thus described my invention, what I claim as new, and desire to secure by Letters Patent, is—

In a portable fire-escape, a spindle, a pair of spools mounted at either end thereof, a 10 cable having its ends secured to the spools and adapted to be wound upon the latter, a slotted hollow handle loosely mounted upon the aforesaid spindle between the spools, a pawl secured to the handle, and a ratchet- 15 wheel fast to the spindle whereby the handle and spindle are normally locked together, a brake-band projecting from one of the spools

in the path of the pawl whereby when the latter is disengaged from the ratchet-wheel it will bear upon the brake-band, another cable 20 secured to the spindle within the hollow handle and adapted to be wound upon the former in the opposite direction from the first-named cable, thimbles loosely mounted upon the aforesaid spindle and a stirrup suspended 25 from the thimbles substantially as set forth.

In testimony that I claim the foregoing I have hereunto set my hand, at Milwaukee, in the county of Milwaukee and State of Wisconsin, in the presence of two witnesses.

MARY JANE JOHNSTON.
